UNITED STATES PATENT OFFICE.

JAMES K. P. PINE, OF LANSINGBURG, NEW YORK, ASSIGNOR TO UNITED SHIRT AND COLLAR COMPANY, OF TROY, NEW YORK, A CORPORATION OF NEW YORK.

COLLAR.

1,253,418.

Specification of Letters Patent. Patented Jan. 15, 1918.

Application filed January 6, 1917. Serial No. 140,880.

To all whom it may concern:

Be it known that I, JAMES K. PINE, a citizen of the United States of America, and a resident of Lansingburg, county of 5 Rensselaer, and State of New York, have invented certain new and useful Improvements in Collars, of which the following is a specification.

My invention relates to new and useful 10 improvements in collars, and more particularly collars of that type generally known as "soft turned-over" or "soft turned-down" collars, which usually include a soft flexible neckband member, and a turned-over portion or member, which is also soft or flexible, and the upper edge portion of which is united to the upper edge portion of the neck-band along a fold line.

My invention particularly contemplates 20 improved and simplified means for stiffening or supporting the soft and easily crushable member of a collar of the style mentioned, so that it will be held extended to its width when in position upon the neck 25 of the wearer. I have shown and described the invention broadly as applied both to the neck-band member, in which case the invention serves to hold the same extended substantially at its intended height or width 30 about the neck of the wearer, and will be prevented from collapsing or becoming crumpled while in use, and also to the soft turned-over portion or member, so that it, and more particularly the front portions 35 or wings thereof, will be held smoothly in position and be prevented from curling or crumpling.

The invention consists in the improvements to be more fully described herein- 40 after, and the novelty of which will be particularly pointed out and distinctly claimed.

I have fully and clearly illustrated the invention in the accompanying drawings, to be taken as a part of this specification, 45 and wherein:—

Figure 1 is a view in front elevation or perspective of one embodiment of my invention, in which the latter is applied to the soft neck-band member of a collar;

50 Fig. 2 is a detailed view of one end of the collar shown in Fig. 1, the turned-over portion being raised to show the outside

of the neck-band member, and the supporting or stiffening means applied thereto;

Fig. 3 is a section on the line 3—3 of 55 Fig. 1;

Fig. 4 is a detailed view of one end of the collar, the turned-over portion being raised to show the invention when applied to the underside of said turned-over portion;

Fig. 5 is a view similar to Fig. 4, but showing a modification.

Fig. 6 is a section on the line 6—6 of 65 Fig. 4.

Fig. 7 is a view showing the turned-over portion raised and the invention applied to both the said portion and the neck-band.

Before proceeding with the detailed description of the preferred embodiment of 70 my invention, I desire to state that the invention is not limited to the particular style of collar shown in drawings, but is applicable to all styles of collars of the general type shown, embodying either a 75 flexible or soft neck-band, and a flexible or soft turned-over portion, or both, irrespective of the general contour of the neck-band and the turned-over portion, or the relative dimensions thereof.

Referring to the drawings by characters of reference, 1 designates generally a collar of a well-known style or type in connection with which my invention is illustrated for purposes of exemplification. This 85 collar includes a flexible or soft neck-band 2, which may be composed of inner and outer plies of fabric 3, 4, and a filling ply 5, which plies are united at the upper, lower and end edges of the neck-band by a marginal line of stitches 6. The ends of the neck-band may be provided with the usual buttonholes 7, 8, by means of which the neck-band of the collar is secured in place on the neck-band of a shirt, and the overlying end of the neck-band may also be provided with a buttonhole 9 to engage with a button 10 secured to the opposite end of the neck-band on the outer or concealed face of the latter.

Connected to the upper edge portion of the neck-band is a soft turned-over portion 11, the upper edge portion 12 of which is inserted between the upper edges of the

plies of the neck-band and secured to the latter by the stitch line 6, heretofore described, in a well known manner. The turned-over portion 11 folds over or turns down along a fold line approximating the stitch line by which it is secured to the neck-band, and when in position to be worn lies upon or adjacent to the outer face of the neck-band. The turned-over portion 10 may consist of the usual inner and outer plies, as shown in Fig. 3, united by a marginal line of stitches 13, and the stitches 6, in a well-known manner.

The collar which I have just described 15 is of a well-known construction, to which I do not desire to be limited, and has been illustrated solely in order that my improvement, which will now be described, will be made clear to those skilled in the art.

20 Referring particularly to Figs. 1, 2 and 3, I will now describe one embodiment of the invention, wherein the improved construction of collar and stiffening means is provided wherein said stiffening means is applied to the soft neck-band member of the collar in order to support the same and prevent collapsing, crumpling or crushing thereof: In this embodiment I provide the outer ply 4 of the neck-band at each end 25 portion thereof, that is that ply which is concealed when the collar is being worn, with a pair of oppositely disposed openings or slits which may be, and preferably are, in the form of buttonholes 14, extending lengthwise of the neck-band. The buttonholes 14 of each pair are preferably arranged parallel to each other, and spaced respectively from the upper and lower edges of the neck-band, and from each other. Although the exact location and number of 30 these pairs of buttonholes may be varied, I prefer to arrange a pair adjacent each end portion of the neck-band, so that when the collar is in place on the neck of the wearer 35 said pairs of buttonholes will be at the front portion of the collar. The buttonholes of each pair are arranged, respectively, a distance from the upper and lower edges of the collar to provide sufficient holding portion 40 of the fabric of the ply between the buttonholes and said upper and lower edges of the neck-band, as at 15, for a purpose to be presently described. The buttonholes may be provided with suitable binding to 45 prevent fraying of the fabric, for instance I may employ the well-known buttonhole stitch, indicated at 16. As will be noted from an examination of Fig. 3, the button-hole 14 is cut only through the outer ply, so 50 as to leave the inner ply 3 and the filling strip 5 intact.

55 Each pair of opposed openings heretofore described is designed and arranged to receive the opposite ends of a stiffening member 17, which is adapted to lie upon the con-

cealed face or outer ply of the neck-band, and of such length that when in said position, its ends will project through the said buttonholes 14 into the space between the plies of the neck-band and under the portions 15 of the outer ply, and thereby be held against accidental displacement. The stiffening member is not only of such length that its ends will be properly seated through said buttonholes, but is preferably such 75 that its extreme ends will engage the marginal seam 6 of the neck-band whereby the stiffening member acts to support and maintain the neck-band in extended position throughout the entire width thereof. The 80 stiffening member may be of any suitable material, such as buckram, featherbone or celluloid, and preferably of such flexibility that its ends may be readily inserted through and removed from the said buttonholes 14. 85

It is apparent that the invention may be applied, without deviating therefrom, to the soft turned-over portion of a collar, and I have so illustrated the same in Figs. 4, 5 and 6, in which the soft neck-band member and the soft turned-over portion may be constructed as described with reference to Figs. 1 to 3 inclusive, which description need not be repeated. In this form of the invention, the under or concealed ply of each end of 90 the turned-over portion is provided with a pair of slits 14^a, preferably in the form of buttonholes arranged parallel to each other, and closely adjacent the upper and lower edges of said turned-over portion. In this 95 form, as is the case with the form shown in Figs. 1 to 3 inclusive, the buttonholes are spaced from each other, and from the upper and lower edges of the turned-over portion, extend in a general direction lengthwise of 100 said portion, and are adapted to receive the opposite ends of a stiffening member 17^a in the same manner as heretofore described. In Figs. 4 and 5 the buttonholes are, as 105 shown, slightly oblique to the upper and lower edges of the turned-over portion, so that when the stiffening member 17^a is in place it will extend longitudinally in a direction substantially parallel to the front edge 18 of the turned-over portion. The dimensions of the stiffening member with reference to the turned-over portion and the buttonholes formed therein are determined 110 in the same manner as the stiffening member when employed on the neck-band. The ends of the member 17^a are preferably beveled off as at 17^b, so as to present a straight edge 115 to the seams 6 and 13.

Instead of having the ends of the stiffening member of such length as to engage the 125 seams of the collar member to which it is applied, I may employ a construction such as is shown in Fig. 5, in which the stiffening member is made somewhat shorter than the width of the collar member, and its 130

movement toward the edge of the collar member, for example the lower edge of the turned-over member 11 is limited by means of a line of stitches 13^a between the button-hole 14^a and the said edge, said line of stitches 13^a uniting the inner ply of the collar member 11, and one or more of the other plies thereof. By this means the end of the stiffening member is prevented from going 10 to the lower edge of the member 11.

In Fig. 7 I have shown a construction in which the invention is applied to both the neck-band member and the turned-over member of a soft collar. In this embodiment the 15 construction and arrangement may be the same as described above, but I prefer to so arrange the buttonhole 14^a and 14^b, that when the stiffening members 17^a are in place and the turned-over portion is turned down 20 onto the neck-band, the said stiffening members will not face each other but will be arranged side by side, as will be clear from the drawings. I have shown and described only 25 one end of a collar constructed according to this embodiment of the invention, but it will be understood that in practice both ends are so provided.

What I claim and desire to secure by Letters Patent of the United States is—

30. 1. As a new article of manufacture, a turned-over collar comprising a substantially upstanding neck-band member, and a turned-over member united along a fold line at the upper portions thereof, one of said 35 members being soft and consisting of inner and outer continuous plies, the inner ply of said soft member having opposed openings spaced from the upper and lower edges thereof, and a stiffening member lying with 40 its length transversely of the collar on the outer face of said inner ply and having its opposite end portions inserted through said openings and located beneath the inner face of said ply.
45. 2. As a new article of manufacture, a turned-over collar comprising a substantially upstanding neck-band member, and a turned-over member united along a fold line at the upper portions thereof, one of said 50 members being soft and consisting of inner and outer continuous plies, the inner ply of said soft member having opposed slits extending lengthwise of said member and spaced from the upper and lower edges 55 thereof, and substantially parallel to each other, and a stiffening member lying on the outer face of said inner ply and having its opposite end portions inserted through said openings and located beneath the inner face 60 of said ply.
65. 3. As a new article of manufacture, a turned-over collar comprising a substantially upstanding neck-band member, and a turned-over member united along a fold line 65 at the upper portions thereof, one of said

members being soft and consisting of inner and outer continuous plies, the inner ply of said soft member having opposed slits extending lengthwise of said member and spaced from the upper and lower edges 70 thereof, and substantially parallel to each other, said slits being bound with stitching, and a stiffening member lying on the outer face of said inner ply and having its opposite end portions inserted through said 75 openings and located beneath the inner face of said ply.

4. As a new article of manufacture, a turned-over collar comprising a substantially upstanding neck-band member, and a turned-over member united along a fold line at the upper portions thereof, one of said members being soft and consisting of inner and outer continuous plies, the inner ply of said soft member having opposed openings 80 spaced from the upper and lower edges thereof, a stiffening member lying on the outer face of said inner ply and having its opposite end portions inserted through said 85 openings and located beneath the inner face 90 of said ply, and a stitch line uniting said plies adjacent the ends of said member.

5. As a new article of manufacture, a turned-over collar comprising a substantially upstanding neck-band member, and a turned-over member united along a fold line at the upper portions thereof, one of said members being soft and consisting of inner and outer continuous plies, the inner 100 ply of the soft member having opposed openings spaced from the upper and lower edges thereof, a stiffening member lying on the outer face of said inner ply and having its opposite end portions inserted through said 105 openings and located beneath the inner face of said ply, a marginal stitch line uniting the plies of said soft member, and a stitch line also uniting said plies and adjacent the ends of said member, said stitch line being 110 located between one of said openings and the adjacent portion of the marginal stitch line.

6. As a new article of manufacture, a turned-over collar comprising a substantially upstanding soft neck-band member, and a soft turned-over member united along a fold line at the upper portions thereof, said members each comprising a plurality of continuous plies, the concealed ply of each member being provided with a pair of 115 openings spaced from the upper and lower edges of the respective members, and a stiffening member lying on the outer face of the concealed ply of each of said collar members and having its ends inserted through said buttonholes and located beneath the inner face of the concealed ply.

7. As a new article of manufacture, a turned-over collar comprising a substantially upstanding soft neck-band member, and a soft turned-over member united along 120

125

130

a fold line at the upper portions thereof, said members each comprising a plurality of continuous plies, the concealed ply of each member being provided with a pair of buttonholes spaced from the upper and lower edges of the respective members, and a stiffening member lying on the outer face of the concealed ply of each of said collar members and having its ends inserted through said buttonholes and located beneath the inner face of the concealed ply,

said pairs of buttonholes being so located that the stiffening members lie side-by-side when the collar is being worn.

In testimony whereof I have hereunto signed my name in the presence of two subscribing witnesses.

JAMES K. P. PINE.
